Friedrich G. Gantz.

ATTORNEYS.

UNITED STATES PATENT OFFICE.

CHARLES W. HOTTMANN, JR., OF SANDUSKY, OHIO, ASSIGNOR TO THE BROWN CLUTCH CO., OF SANDUSKY, OHIO, A CORPORATION OF OHIO.

WASHING MACHINE.

1,414,468.

Specification of Letters Patent. Patented May 2, 1922.

Application filed February 18, 1922. Serial No. 537,430.

To all whom it may concern:

Be it known that I, CHARLES W. HOTTMANN, Jr., a citizen of the United States, residing at Sandusky, county of Erie, State of Ohio, have invented a new and useful 5 Washing Machine, of which the following is a specification.

My invention comprehends a novel construction and arrangement of a washing machine of the type in which the dolly or agitator is carried by a support which latter is adapted to be secured to wash-tubs, barrels or similar open ended containers in which it is desired to agitate the material which they 10 contain.

My invention further comprehends a novel construction and arrangement of a supporting mechanism which is adapted to be secured to the upper portion of containers of 15 different diameters.

It further comprehends a novel construction of a supporting mechanism of the type referred to wherein a plurality of supporting arms are provided which are operatively 20 connected with each other so that they can be simultaneously and uniformly adjusted.

It further comprehends a novel construction of supporting arm and novel fastening devices therefor.

30 Other novel features of construction and advantage will hereinafter be more fully set forth.

For the purpose of illustrating my invention, I have shown in the accompanying 35 drawings a typical embodiment thereof which is at present preferred by me, since this embodiment will be found in practice to give satisfactory and reliable results. It is, however, to be understood that the various 40 instrumentalities of which my invention consists can be variously arranged and organized and that my invention is not limited to the precise arrangement and organization of these instrumentalities as herein shown and 45 described.

Figure 1 represents, in side elevation, partly broken away, a washing machine, embodying my invention, in conjunction with a conventional type of tub.

50 Figure 2 represents a bottom plan view of the supporting mechanism.

Figure 3 represents a section on line 3—3 of Figure 2.

Similar numerals of reference indicate corresponding parts.

Referring to the drawings.

1 designates a tub, such as for example a washing tub, it being understood that any kind of container may be employed. 2 designates the ordinary dolly or agitating device which is provided with a shaft 3 which is guided and supported by means of a novel construction and arrangement of agitating support embodying my invention. 4 designates the body portion of the support which may be formed of pressed steel having a central hub 5 and the depending flange 6 at its outer periphery. 7 designates a plurality of arms preferably formed of pressed metal or castings and having integral therewith at 70 their inner ends the gears 8 which are adapted to mesh with a gear 9 rotatably mounted on the hub 5. Two of the arms are pivotally connected with the body portion 4 by means of rivets 10 while the other arm 7 is connected with the body portion 4 by means of a screw 11 in the thumb nut 12. Each of the arms 7 are preferably curved and are provided near their outer periphery with the downwardly and outwardly deflected flange 80 13 which engages the inner wall of the tub 1. 14 designates brackets secured to an arm 7 by means of a rivet 15 and having a recess 16 into which the extension 17 of an arm is seated so that the bracket 14 is rigidly connected with its arm. The bracket 14 is provided with a depending flange 18 with which 85 has threaded engagement a screw 19 which is screwed against the outer wall of the tub 1 to secure the arm in position with respect to the washing tub. The dolly shaft 3 is provided with a gear 20 with which meshes the operating gear 21 mounted in the bracket 22 carried by the body portion 4 in any desired manner and the gear 21 is rocked 90 by means of its actuating handle 23.

The operation will now be readily apparent and is as follows:—

In order to assemble the mechanism with respect to a wash tub all that it is necessary 100 to do is place the arms 7 over the tub so that they will rest on the rim thereof and since all of these arms are intergeared the adjustment of one will adjust them all. The thumb nuts 12 are then tightened and the screws 19 105 105 so that the washing mechanism is rigidly

connected with respect to the wash tub. The dolly is oscillated in the usual manner by actuating the handle 23. My device can be economically manufactured as the parts 5 can be readily cast or made from sheet metal. It will be seen that the gear 9 is loosely mounted on the hub 5 and is retained in place by the arm 7.

It will now be apparent that I have devised a novel and useful washing machine 10 which embodies the features of advantage enumerated as desirable in the statement of the invention and the above description, and while I have, in the present invention, shown 15 and described an embodiment thereof which will give in practice satisfactory and reliable results, it is to be understood that such embodiment is susceptible of modification in various particulars without departing from 20 the spirit or scope of the invention or sacrificing any of its advantages.

Having thus described my invention, what I claim as new and desire to secure by Letters Patent, is:

- 25 1. In a washing machine, a dolly support comprising a body portion, a gear loosely mounted thereon, a plurality of arms pivotally carried by said body portion and intergeared with said gear, and fastening devices to secure said arms with respect to a tub.
- 30 2. In a washing machine, a dolly support comprising a body portion, a gear loosely mounted thereon, a plurality of arms pivotally carried by said body portion and intergeared with said gear, said arms having

near their outer end depending flanges adapted to engage a tub, and fastening devices to secure said arms with respect to a tub.

3. In a washing machine, a dolly support 40 comprising a body portion having an apertured hub adapted to receive a dolly shaft, a gear loosely mounted on said hub, a plurality of arms pivotally carried by said body portion and intergeared with said gear and serving to retain said loosely mounted gear in position, and fastening devices carried by said arms.

4. In a washing machine, a dolly support 45 comprising a body portion, a gear loosely mounted on it, arms having gears to mesh with said loosely mounted gear, said arms being pivoted to said body portion and having one of its pivots adjustable, and fastening devices carried by said arms.

5. In a washing machine, a dolly support 50 comprising a body portion, a gear loosely mounted on said body portion, a plurality of arms movably carried by said body portion and intergeared with said gear, whereby the position of said arms can be simultaneously adjusted, said arms having near their outer ends depending flanges, brackets carried at the outer ends of said arms, and fastening devices carried by said brackets to 55 secure the wall of a tub against said flanges.
